Primary Examiner—C. A. Murphy*Attorney, Agent, or Firm*—Middleton & Reutlinger; David W. Carrithers[57] **CLAIM**

The ornamental design for a cape, as shown and described.

DESCRIPTION

FIG. 1 is a top plan view of a cape showing my new design, the broken lines showing legible indicia being for illustrative purposes only and forming no part of the claimed design; FIG. 2 is a left side elevational view thereof; FIG. 3 is a front elevational view thereof; FIG. 4 is a right side elevational view thereof; FIG. 5 is a rear elevational view thereof; FIG. 6 is a bottom plan view thereof; FIG. 7 is a top plan view thereof shown in a flattened condition; FIG. 8 is a right side elevational view of FIG. 7; FIG. 9 is a rear elevational view of FIG. 7; FIG. 10 is a left side elevational view of FIG. 7; FIG. 11 is a bottom plan view of FIG. 7; and, FIG. 12 is a bottom plan view of FIG. 7. The parallel broken lines following the contour of the claimed article in FIGS. 1 through 6, 9 and 12 are understood to represent conventional stitching.
